UNITED STATES PATENT OFFICE.

WILHELM RAYDT, OF HANOVER, PRUSSIA, GERMANY.

APPARATUS FOR MAKING AERATED WATER.

SPECIFICATION forming part of Letters Patent No. 358,165, dated February 22, 1887.

Application filed June 15, 1885. Serial No. 168,774. (No model.)

To all whom it may concern:

Be it known that I, WILHELM RAYDT, doctor of philosophy, a subject of the King of Prussia, residing at Hanover, Prussia, German Empire, have invented certain new and useful Improvements in Apparatus for Making Aerated Waters; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

This invention relates to apparatus for the production of artificial mineral waters or other effervescent liquids by impregnation with carbonic-acid gas obtained directly from fluid carbonic acid.

Artificial mineral waters—that is to say, such waters as contain, besides mineral substances or constituents, principally carbonic acid—have heretofore been charged with carbonic-acid gas generated in suitable apparatus connected with the charging or impregnating vessel either at the place of consumption or at special establishments where such liquids are manufactured for charging the water with carbonic-acid gas and forcing the same from the vessel in which it is contained. The carbonic-acid gas is usually obtained by the reaction of an acid upon carbonates or by heating bicarbonates. This mode of obtaining the gas is very inconvenient in that it becomes necessary to charge the generator from time to time with a carbonate or with a bicarbonate, in which latter case it is necessary to apply heat to the generator. On the other hand, the gases must be kept under sufficient pressure before they can be admitted to the water to be charged or impregnated therewith. By means of the described mode of obtaining the carbonic-acid gas it is extremely difficult, if not impossible, to obtain a gas free from atmospheric air and chemically pure, so that the water charged frequently contains substances or elements that are deleterious to health, and in view of the air combined with the gas the impregnation of the liquid is necessarily incomplete, and such water will give up most of its carbonic acid if the vessel or bottle containing the same remains open a short while. Finally, the manu-

facture of the artificial mineral or other water by the processes described, and the apparatus required therefor, are costly and complicated, and their management requires experienced as well as skilled operators.

The object of this invention is to provide means whereby the described inconveniences are avoided, and whereby the process of manufacture is not only simplified, so as to come within the reach of ordinary mechanics, but whereby the cost of manufacture is materially reduced.

The further object of this invention is to provide means whereby liquids may be impregnated with, I may say, absolutely chemically-pure carbonic-acid gas. The latter result I obtain by the use of liquid carbonic acid instead of generating the gas from the chemicals above mentioned or other chemicals, as usual; and the invention consists in the construction of the apparatus and the combination of its several parts, substantially as hereinafter fully described, and as shown in the accompanying drawing, in which I have illustrated my improved apparatus by a vertical sectional elevation.

The apparatus is composed of a flask, A, that contains liquid carbonic acid, a gas-holder, B, a charging-vessel, C, and a pump, D.

The flask A is a cylindrical vessel of sufficient strength, in the head of which is screwed a valve-casing, a, containing a needle or conical valve, b', the stem b of which is screwed in a stuffing-box, a', and projects through the gland or cap a² thereof, the outer end of said spindle being squared for the application of a key for rotating the same to open or close the passage d of the valve-casing a. The passage d of valve-casing a communicates with a chamber, c, formed in said casing, in which is arranged a packing-gland, a³, through which the valve-spindle b passes.

The valve-casing a has a branch, e, that communicates with the chamber c, and to said branch is connected one end of a pipe, f, the other end of which is connected to a branch, g, of the valve-casing G, secured to the upper end of the gas-holder B. The valve casing G is provided at its upper end with a weighted safety-valve, l, that closes the passage g', which extends through the valve-casing, and k is the weight of the valve l. The valve-casing G has

a second branch, g^2 , in which is arranged a screw-valve, h , adapted to cut off the communication between the flask A and holder B. To a third branch, g^3 , of the valve-casing is secured a manometer, n , for obvious purposes, and to a fourth branch, g^4 , provided with a valve or stop-cock, r , is connected one end of a pipe, s , the opposite end of which is connected with the impregnating or charging vessel or cylinder C. The latter cylinder is also provided with a manometer or pressure-gage, w , a blow-off cock, x , a discharge-pipe, v , and stirrers or beaters c , mounted on a shaft, E, adapted to be rotated either by power derived from any suitable prime motor or by means of the crank F. The cylinder C is also connected, by means of a pipe, u , provided with a valve, m , with a suction and compressing pump, D.

The pipe s at its junction with the vessel C is provided with a valve or stop-cock, t , for purposes presently explained.

The operation of the apparatus is as follows: The liquid to be charged with carbonic-acid gas is pumped by pump D into the vessel C until the latter is about two-thirds full, (more or less,) when the cut-off cock m is closed. The valves b' h are now opened, to allow the carbonic acid in flask A to expand and pass, in the form of carbonic-acid gas, to the holder C until the manometer n indicates a pressure of from four to five atmospheres, which will take place very rapidly, as the tension of the fluid carbonic acid is about forty atmospheres, which tension or pressure is diminished as the acid in flask A volatilizes. The valves b' and h are then closed, and those, r t , in pipe s opened to allow the gas to flow from holder B into the impregnating or charging cylinder C. In order to remove the air from cylinder C, as well as the air that may be combined with the liquid to be charged with carbonic-acid gas, the said liquid is agitated by rotating the shaft E, and charged with carbonic-acid gas under a pressure of about two atmospheres. One or both stop-cocks or valves r t is or are then closed, and the blow-off cock x opened to allow the air and a portion of the carbonic-acid gas to escape from cylinder C, after which the blow-off cock is closed and carbonic-acid gas again admitted to cylinder C by opening cocks or valves r t , or either of them, as the case may be. The beaters are set in operation, and the process of charging or impregnating is continued until the manometer n indicates an invariable pressure in the cylinder C, which will take place after the lapse of a few minutes, when the liquid will be saturated with carbonic-acid gas, and may then be drawn off through pipe v to any suitable bottling apparatus, or into vessels for storing such charged liquid.

The pressure in cylinder C during the discharge or bottling of the contents thereof will be materially reduced, and to avoid this I allow carbonic-acid gas to flow into the cylinder to prevent any material reduction of the pressure therein. After the liquid in vessel C

has been discharged the carbonic-acid gas remaining behind may be utilized by recharging the cylinder with water, through the medium of the pump, or by admitting water thereto under a sufficient pressure—as, for instance, from a water-main—the blow-off cock remaining closed during the filling of the apparatus, and it is only opened for a very short time to expel the air from the fresh charge of water after having agitated the latter.

It will be understood that the relative arrangement of the various parts that constitute the apparatus may differ from that shown in the drawing without departing from the nature of the invention.

Instead of valves, stop-cocks may be employed, and the manometer n may be connected with the holder B directly, instead of connecting the same indirectly therewith through the valve-casing, and the safety-valve may be interposed in the connection at any suitable point.

In my improved apparatus the generator for the carbonic acid is dispensed with, which is a great advantage over the apparatus of this class heretofore used. The fluid acid being manufactured or produced in special establishments, and on a large scale, may therefore not only be obtained in a chemically-pure state, but also at a greatly reduced cost, and such acid does not contain any appreciable volume of atmospheric air, since the pressure of the latter in appreciable volume would not admit of a fluid condition of the acid. When the flask A is empty, it can be readily disconnected from the pipe f and a filled flask substituted therefor.

The use of carbonic acid free from atmospheric air and chemically pure in itself insures a more healthy and better product than is the case where the gas is generated from chemicals or substances capable of giving off carbonic-acid gas by the reaction of an acid, and offers the further advantage that a quantity of the fluid acid capable of evolving large volumes of gases may be stored in a comparatively small space, since one liter of fluid carbonic acid produces four hundred and fifty liters of carbonic-acid gas. The conversion of the fluid acid into gas also results in an absorption of heat—that is to say, in a considerable reduction of the temperature of the liquid charged therewith, which facilitates the impregnation or charging of the said liquid, while in all the methods heretofore in use heat is developed in the process of generating the gas, which renders the impregnation or charging of the liquid difficult.

What I claim is—

1. An apparatus for charging liquids with carbonic-acid gas, consisting of a flask, A, containing liquid carbonic acid, and a gas-holder connected with the flask A, for storing the gases evolved by expansion of the liquid carbonic acid in said flask, and a valve interposed in said connection, in combination with a receiver for receiving the liquid to be charged,

a pipe connecting the receiver with the gas-holder, and a valve interposed in said connection, substantially as and for the purpose specified.

5 2. The combination, substantially as herein described, with the flask A, containing liquid carbonic acid, the gas-holder B, and receiver C, connected thereto, of a cut-off valve interposed in each of the connections between the
10 gas-holder, the flask, and receiver, and a safety-

valve in the connection between the gas-holder and flask interposed between the cut-off valve and said flask, substantially as and for the purpose specified.

In testimony whereof I affix my signature in 15 presence of two witnesses.

WILHELM RAYDT.
